US00D978959S

(12) **United States Design Patent** (10) **Patent No.:** **US D978,959 S**
(45) **Date of Patent:** **** Feb. 21, 2023**

(54) **EYEGLASSES**

(71) Applicant: **Kai Fang**, Wenzhou (CH)

(72) Inventor: **Kai Fang**, Wenzhou (CH)

(**) Term: **15 Years**

(21) Appl. No.: **29/770,332**

(22) Filed: **Feb. 11, 2021**
Related U.S. Application Data

(63) Continuation-in-part of application No. 29/763,177, filed on Dec. 21, 2020, and a continuation-in-part of application No. 29/763,174, filed on Dec. 21, 2020, and a continuation-in-part of application No. 29/762,305, filed on Dec. 16, 2020, and a continuation-in-part of application No. 29/762,308, filed on Dec. 16, 2020, and a continuation-in-part of application No. 29/754,294, filed on Oct. 9, 2020, and a continuation-in-part of application No. 29/754,293, filed on Oct. 9, 2020, and a continuation-in-part of application No. 29/753,054, filed on Sep. 29, 2020, and a continuation-in-part of application No. 29/750,673, filed on Sep. 16, 2020, now Pat. No. Des. 954,810, and a continuation-in-part of application No. 29/749,743, filed on Sep. 9, 2020.
